Patented Aug. 17, 1926.

UNITED STATES PATENT OFFICE.

FRED S. ENGLISH, OF NEW LONDON, CONNECTICUT.

CUTTING AND CREEASING PRESS.

Application filed March 2, 1923. Serial No. 622,414.

My invention relates to presses for cutting and creasing sheets of paper, cardboard or other stock and the invention may be applied to a printing press which is used for cutting and creasing or to a press specially built for cutting and creasing. The invention is herein shown applied to a flat bed press though it will be apparent that my invention is not limited to this application.

10 This is made up from sharp edged cutting rule and round edged creasing rule placed edgeways in the form which is carried on the bed and held in position by means of wooden or metal blocks.

15 A sheet of box board is fed to the cylinder, and as it passes between the bed and the cylinder it is cut into suitable sections to make boxes and is suitably creased for bending at the corners of the boxes.

20 It is customary to leave ties or tabs connecting various portions of the sheets connected where they would be otherwise entirely severed by the cutting rules, in order that sections of the sheet will be temporarily

25 held together until the sheet is delivered from the press, the sheets being "stripped" after they are delivered from the press to remove or break these ties or tabs. It often happens that these ties or bands are not 30 strong enough to prevent portions of the cut and creased sheets from separating before they are delivered from the press and the present invention is intended to prevent injury to the sheets, the form and the press if 35 such occurs.

The general method of cutting and creasing these sheets is described in my Patent No. 1,375,450.

40 After the sheet is cut and before it is delivered from the cylinder, these cut sections are likely to fall out and either cause trouble on the delivery or they may drop on to the die and interfere with cutting the next sheet.

45 The present invention covers an easily removable shield, or series of bands at the back of the cylinder. It is necessary to make this shield easily removable in order to make room to lift the jacket for make ready as described in my Patent No. 1,375,450.

50 In the drawings forming part of the application,

Fig. I is a side elevation of an ordinary cutting and creasing press with my invention attached.

Fig. II is an enlarged side view of some 55 of the parts showing the shield or bands.

Figs. III and IV are enlarged detail sections showing a method of adjusting the shield supporting brackets.

Fig. V is a sectional plan of the end of one 60 of the brackets showing a collar for holding the supporting rods in place.

Fig. VI is a back view of the shield or bands, and the cylinder.

In Figure I I have shown only such portions of a press as are necessary to illustrate the application of my invention. Herein I have shown one of the side frames 15 of the press, the feed table, 2, from which the sheets are fed, the impression cylinder 1—the sheet 70 delivering device 7 for delivering the sheet from the cylinder, and the reciprocating bed 3, having a form 4 of cutting and creasing rules.

In Figure I the impression cylinder is 75 shown in position to take a sheet from the feed table, 2, and as the cylinder revolves in the direction of the arrow, it carries the sheet around with it. At this time the bed 3, is moving toward the cylinder (in the direction of its arrow) and as the bed runs under the cylinder, the die 4, cuts and creases the sheet on the cylinder. The cut sheet now passes on up with the cylinder at 5 and during this time cut portions are likely to fall 85 out on to the die, which has now come into position 6 or to the rear of the impression cylinder, or if they do not fall entirely out they may come partly out, and these hanging portions are likely to catch on some part 90 of the delivery at 7 for instance, and thus throw the sheet out of position in the delivery.

At 8 I have shown a shield or series of bands bent approximately to the curve of the 95 cylinder; this shield is fastened to small supporting blocks or brackets 9 and 10, which hang on the rods 11 and 12.

These rods are supported on brackets 13 and 14 attached to any part of the frame 100 work of the press such as the frame members 15. Since some jobs require the shield closer

to the cylinder than others, it is desirable to make it adjustable to and from the cylinder. It is also well for convenience in manufacturing to make the brackets adjustable 5 (slightly) up and down. I have accomplished this as follows:—

Bracket 13 is attached to the frame with two bolts, one of which passes through a hole 16 and the other through a slot 17 in the 10 bracket, Fig. III. Thus the bracket 13 can be swung slightly toward or away from the cylinder (after slackening off the bolts). Bracket 14 is attached with two bolts, one through a large hole 18, and the other a 15 slot 19, in the bracket, Fig. IV. Thus, if the bolts are slackened off, bracket 14 can be adjusted towards or away from the cylinder and it can be swung up and down slightly.

When lifting the jacket for make ready, 20 it is necessary to remove this shield bodily from the cylinder. I have made it easily removable as follows:—

The rods 11 and 12 are held together by means of the connecting arms 20, thus the 25 rods, arms and shield make one complete unit and can be handled as such. The rods 11 and 12 hang in slots 40, 41, in their brackets. The top rod 11 will be automatically held in position by gravity and the bottom 30 rod is held in position by means of spring collars and lugs in the bracket, thus:

Brackets 14 are provided with lugs 24. (These show best in Fig. V.) Shaft 12 is provided with a fixed collar 23, at one end 35 and a movable collar 22 at the other end and the movable collar is held in position by means of a spring 21. When the shaft 12 is seated in its slots the collars 22 and 23 are also seated against the face of the 40 bracket, back of lugs 24, and it is effectually held there by means of the spring 21 so that the rod cannot get out without first sliding the spring collar along in its rod. At 25 is a pin in the rod 12 to hold the collar 22 from sliding entirely off the rod 45 when the unit is removed from the brackets. Since collar 23 is fixed in the rod, it can readily be made as an integral part of the rod if it is desired, i. e., as a shoulder on 50 the rod.

To remove the shield, the unit is grasped at any convenient place, say by the arms 20, and it is moved slightly to the right, Fig. VI, compressing spring 21, until the collar 55 23 slips by the lugs 24. This corner is removed from its bracket, and the unit is slid to the left until the collar 22 slips by its lugs, and then the entire unit is lifted straight up and out of the slots in brackets 13. To re- 60 place the unit the process is reversed.

This shield can be made of one continuous piece, or of a series of strips or bands, two of which are shown at 8, Fig. VI.

I have shown this device as attached to a

bed and cylinder cutter and creaser, but it 65 is evident that it is equally applicable to other types of cutters and creasers as well and it should be so considered.

Having described my invention, what I 70 claim is:

1. In a cutter and creaser press an impression cylinder for carrying the sheet, and a shield adjacent the after part of the cylinder and co-operating with the cylinder to cause the sheet to travel therewith after the 75 sheet has received an impression.

2. In a cutter and creaser press the combination of an impression cylinder adapted to carry the sheet, and a shield, and means for adjustably attaching the shield adjacent the after part of the cylinder, said shield co-operating with the cylinder for the purpose of causing the sheet to travel with the cylinder after receiving an impression.

3. In a cutter and creaser press the combination of an impression cylinder for carrying the sheet, and a quickly removable shield adjacent the after part of the cylinder and co-operating with the cylinder to cause the sheet to follow the same after receiving 90 an impression, and means for adjusting the position of the shield relatively to the cylinder.

4. In a cutter and creaser press the combination of an impression cylinder for carrying the sheet and quickly removable series of bands adjacent the after portion of the cylinder and co-operating therewith to cause the sheet to follow the cylinder after receiving 95 an impression.

5. In a cutter and creaser press the combination of an impression cylinder for carrying the sheets and easily removable series of bands adjacent the after portion of the cylinder and adapted to co-operate therewith for the purpose of causing the sheet to follow the cylinder after receiving an impression, and means for adjusting the position of the bands relatively to the cylinder.

6. In a cutter and creaser press the combination of an impression cylinder, a shield cooperating with the after portion of cylinder to cause the sheet to follow the cylinder after receiving an impression and a set of supports, rods and brackets for supporting said shield in cooperative relation to said cylinder for the purpose set forth.

7. In a cutter and creaser press the combination of an impression cylinder, a shield cooperating with the after portion of the cylinder to cause the sheet to follow the cylinder after receiving an impression, and a set of supporting rods and brackets for supporting said shield in cooperative relation to said cylinder and adapted to permit of the adjustment of said shield toward or from the cylinder.

8. In a cutter and creaser press the com-

- 5 combination of an impression cylinder, a shield cooperating with the after portion of said cylinder to cause the sheet to follow the cylinder after receiving an impression, supporting brackets for said shield, supporting rods on said shield, and spring means for detachably holding said rods on said brackets.
9. In a cutter and creaser press the combination of an impression cylinder, a shield 10 cooperating with the after portion of the cylinder to cause the sheet to follow the cylinder after receiving an impression and comprising the shielding means and a set of spaced rods held together by arms, brackets 15 for supporting said shield and spring means for detachably holding said shield on said brackets.
10. In a cutter and creaser press the combination of an impression cylinder, a shield 20 cooperating with the after portion of said cylinder to cause the sheet to follow the cylinder after receiving an impression, said shield having a supporting rod, brackets for 25 holding said rod, and an adjustable collar on said rod for holding the shield on said brackets.
11. In a cutter and creaser press the combination of an impression cylinder, a shield 30 cooperating with the after portion of said cylinder to cause the sheet to follow the cylinder after receiving an impression, said shield having a supporting rod, brackets for holding said rod, and a spring pressed col-
- lar for said rod for holding the shield on said brackets. 35
12. In a cutter and creaser press the combination of an impression cylinder, a shield 40 cooperating with the after portion of said cylinder to cause the sheet to follow the cylinder after receiving an impression, said shield having a set of supporting rods, said shield and rods forming a detachable unit, and means for detachably holding said unit 45 on said brackets.
13. In a cutter and creaser press the combination of an impression cylinder, a shield 50 cooperating with the after portion of said cylinder to cause the sheet to follow the cylinder after receiving an impression, said shield having supporting rods, and brackets having slots to receive said rods and adapted to support said shield in cooperative relation to said cylinder. 55
14. In a cutter and creaser press the combination of an impression cylinder, a shield 60 cooperating with the after portion of said cylinder to cause the sheet to follow the cylinder after receiving an impression, said shield having supporting rods, brackets having slots to receive said rods, and means for adjusting said brackets to adjust the position of said shield in relation to the cylinder. 65

Signed at the city of New London, county of New London and State of Connecticut, this 21st day of February, 1923.

FRED S. ENGLISH.
